UNITED STATES PATENT OFFICE.

ERNEST H. SHAFF, OF GRAND HAVEN, MICHIGAN, ASSIGNOR TO WILLIAM H. KELLER, INC., OF GRAND HAVEN, MICHIGAN, A CORPORATION OF MICHIGAN.

FLUID-PRESSURE-ACTUATED TOOL.

Application filed December 15, 1920. Serial No. 430,890.

My invention relates to fluid-pressure-actuated tools and more specifically to an improvement in tools of the general type disclosed and claimed in my copending applications Serial No. 371,445, filed April 5, 1920, and Serial No. 417,320, filed October 16, 1920.

One object of the invention is to provide means whereby tools of this type may be operated at slower speeds than heretofore.

Another object of the invention is to provide for a more rapid decrease in the pressure returning the piston toward the end of the stroke than has heretofore been obtainable, thereby reducing the recoil at the end of the return stroke.

Another object is to accomplish this decrease in pressure and provide for slow operation with a minimum loss of pressure fluid.

Further objects and advantages of my invention will become apparent as the description proceeds.

In the accompanying drawings, Figure 1 is a longitudinal sectional view of a pneumatic hammer illustrating the application of my invention thereto and Fig. 2 is a similar view on a somewhat enlarged scale showing the valve in the other position. Fig. 3 is a fragmentary longitudinal sectional view illustrating a detail of construction. The general construction and operation of this type of hammer being disclosed in detail in my copending application Serial No. 371,445, hereinabove referred to, detailed explanation thereof is deemed unnecessary. The tool comprises, briefly, a body member 10 defining a cylinder in which the piston 12 reciprocates to strike a suitable working tool 14; a valve casing comprising annular members 16 and 18 supporting and guiding the valve 20, and a head 22 threaded onto the body and locked in assembled position by a locking clip 24. A throttle valve controlled by the lever 26 delivers air through passage 28 to an annular chamber 30.

With the valve in the position shown in Fig. 1, live motive fluid enters through radial passages 32 terminating in the annular groove 34 and forces the piston forward to strike a blow against the tool. The dead air in front of the piston flows from the front end of the tool through one or more passages 36 to the annular groove 38 in the valve casing which, as shown in Fig. 1, is

in communication with the exhaust groove 40 from which exhaust groove, passages 42 opening under the clip 24 allow the fluid to escape into the atmosphere.

In its forward movement the piston uncovers the small port 44 which raises the pressure in the passage 46 considerably before the piston toward the end of its stroke covers the end of passage 48 and uncovers the end of passage 46. When this occurs, live motive fluid flows through passage 46 and enters the large valve chamber 50. The point at which the valve shifts, however, is determined by the position of the forward end of the piston, because until the forward end of the passage 48 is covered by the piston the pressure in the large pressure chamber 50 is vented to the atmosphere through the forward passage 48, the forward piston chamber and the passage 36. Thus if, as is sometimes the case, an extremely short piston is used, so that the forward end of the passage 46 is uncovered before the forward end of the passage 48 is covered by the piston, the latter passage, acting to vent the large forward pressure area, prevents a premature shifting of the valve. Consequently the valve shifts only when the forward end of the piston is the proper distance from the rivet set 14. After the initial rearward movement of the valve has taken place, the extreme forward end thereof becomes exposed to the live pressure in the rear piston chamber and this high pressure accelerates the rearward movement of the valve. The valve is held in its rear position by motive fluid trapped in the passage 48 by the rearward movement of the valve cutting off the passage 46 from the large valve chamber 50. The air in chamber 50 back of the valve flange may escape through passage 51 into exhaust passage 42. During this movement of the valve live motive fluid fills the passage 48 which, after passage 46 has been cut off from the large valve chamber 50, continues to exert pressure on the valve and hold it in its rearmost position.

The movement of the valve to the position shown in Fig. 2 covers groove 34 and uncovers the exhaust groove 40 so that live motive fluid is cut off from the rear portion of the cylinder and the latter is placed in direct communication with the atmosphere, thus relieving pressure upon the rear end of the valve. The valve in its rearward move-

ment also uncovers the forward end of a passage 52 (Fig. 3) putting it into communication with groove 38 and passage 36. Passage 52 extends radially outward at 54 to receive live motive fluid from the annular chamber 30, which fluid is delivered through passage 36 to the front end of the cylinder to return the piston. On account of the relatively small size of passage 52, the pressure 10 during the return stroke will fall off rather rapidly especially toward the end of the stroke when the piston has attained a fairly high velocity. When the piston on its return stroke uncovers passage 48, the fluid in 15 this passage will fall to the same pressure as that in the front end of the cylinder, which pressure as above noted will decrease considerably during the return stroke.

Farther on in its rearward movement the 20 piston uncovers the forward end of passage 46 and port 44 placing the forward piston chamber in communication with the atmosphere through the passage 46 and the port 62 at the extreme forward end of the valve 25 chamber. This port in the rearward position of the valve communicates with groove 40 connected with the atmosphere by exhaust ports 42. If the hammer is running at full speed very little pressure fluid will 30 exhaust from the forward piston chamber, but the arrangement permits of such exhaust in the event that the hammer is running at low speed, so as to prevent a building up of pressure in the forward piston chamber 35 which would flow through passage 48 to the large valve chamber 50 and prevent the valve from shifting forward.

Toward the end of the return stroke the 40 piston covers the end of the passage 56, the other end of which communicates with the small valve chamber 58. A small port 60 continuously communicates with this passage and with the annular chamber 30. The pressure in the passage 56 cannot rise during the return stroke because the end of the 45 passage is in communication with the rear end of the cylinder until the piston covers it. When this occurs, the pressure in the passage 56 immediately rises and the valve is thrown forward again into the position 50 shown in Fig. 1. This takes place against the pressure existing at the instant in the large valve chamber 50 which is the same as the pressure in the front end of the cylinder 55 by reason of passage 48 which is continually in communication with the large valve chamber and the front end of the cylinder. As soon as the valve has shifted, however, the front end of the cylinder is again connected 60 to the exhaust passages through passage 36 so that during the forward stroke the pressure in the large valve chamber will be practically atmospheric and the valve will be held firmly in the position shown in Fig. 1.

65 During the initial portion of the forward

movement of the valve member there is no pressure on the forward end thereof, but as soon as the groove 40 is covered the forward end of the valve is subjected to the same pressure as exists in the forward piston chamber through the port 62 and the passage 46, the piston being near the forward end of its travel. This serves to retard the forward movement of the valve and opens the inlet groove 34 gradually so as to prevent a large amount of motive fluid from suddenly entering the rear piston chamber and striking the rearwardly moving piston. Thus the piston is brought to a stop gradually and the vibration or kick-back of the 80 tool greatly lessened.

It is often desirable for the workman to strike one or two light preliminary blows before delivering full power to the tool, and for this purpose the supply of air to the tool is throttled. When the supply of air is throttled down by the workman, a limit is reached below which the tool will not operate and this limit occurs when with the piston in its rearmost position and the valve in the position shown in Fig. 2, the supply pressure in the small valve chamber 58 is not sufficient to shift the valve forward. The point at which this limit is reached depends largely on the pressure in the front end of the cylinder, which through passage 48 controls the pressure in the large valve chamber.

According to my invention, I provide a small auxiliary port 62 extending from passage 46 toward the chamber adjacent the exhaust groove 40 so as to be covered by the end of the valve during the forward stroke. When in the forward travel of the piston the forward end of passage 46 is uncovered by the piston, pressure is admitted by the port 62 to the pressure area formed by the forward end of the valve to assist in shifting the valve rearwardly. When the valve shifts rearwardly this port opening directly into the cylinder adjacent the exhaust passages connects the end of passage 46 directly with the atmosphere. When the piston uncovers the end of passage 46 in its rearward travel, therefore, the space in front of the piston is immediately connected with the atmosphere so that the pressure will drop rapidly, the piston travelling the remainder of the rearward stroke with relatively little further increase in speed. It is thus possible by slightly increasing the size of passage 52 to secure the same speed of operation by accelerating the piston faster during the first half of the return stroke and less after passage 46 is uncovered, getting the piston back to the rear end of the cylinder in the same length of time, but with a materially lower final velocity and with less pressure in front of it at the instant of reversal. The decrease in the pres-

sure in the front of the piston accomplishes the same decrease in passages 48 and in the large valve chamber 50, which decrease cuts down on the resistance to forward shifting 5 of the valve, making the forward movement of the same quicker and more uniform and certain. Also the port 62 serves to vent the extreme forward end of the valve during the forward shifting movement thereof, 10 thus preventing a premature building up of pressure at this point, and on the other hand when the groove 40 has been closed in the forward movement of the valve, this port 62 serves to supply air, to retard and 15 cushion the final portion of the movement of the valve.

While I have illustrated and described in detail the preferred embodiment of my invention, it should be clearly understood that 20 the disclosure is merely for purposes of illustration and that many modifications and variations will naturally occur to those skilled in the art. I aim in the subjoined claims to cover all such legitimate variations and modifications.

I claim as my invention:

1. In a fluid-pressure-actuated tool, having a reciprocating piston, means including a valve for delivering live motive fluid to 30 reciprocate the piston, and means controlled by said valve so as to be operative during the latter portion of the return stroke of the piston to cut down the pressure returning the piston, said means being inoperative 35 during the entire forward stroke.

2. In a fluid-pressure-actuated tool having a reciprocating piston, a valve, means for delivering live motive fluid to reciprocate the piston, passageways connected by 40 movement of the valve to effect the return stroke of the piston, and means rendered operative upon such movement of the valve and by the movement of the piston past a predetermined point in the return stroke 45 for cutting down the pressure returning the piston.

3. In a fluid-pressure-actuated tool having a reciprocating piston, an automatic valve controlling the movement of the piston, a valve control passage uncovered by the piston toward the end of the forward stroke for shifting the valve, means for again shifting the valve toward the end of 50 the rearward stroke, and discharge means associated with the valve control passage and uncovered by the valve in its rearward movement whereby uncovering said passage by the piston on its return stroke will operate during the remainder of the stroke to 55 reduce the pressure returning the piston.

4. In a fluid-pressure-actuated tool having a reciprocating piston, a passageway uncovered by the rear end of the piston toward the end of the forward stroke and by 60 the front end of the piston during the rear-

ward stroke, a valve, and means including part of the valve for automatically connecting said passageway to a valve chamber to control the movement of the valve during the forward stroke, and for disconnecting 70 it from said valve chamber and connecting it to the atmosphere during the rearward stroke.

5. In a fluid-pressure-actuated tool having a reciprocating piston and a valve, means for returning the piston in a minimum time with a minimum final velocity comprising means for imparting a high acceleration to the piston at the beginning of the return stroke by delivering motive fluid 80 at high pressure to the front end of the cylinder, and two independent means for diminishing the acceleration during the stroke by cutting down the pressure, one means operating by limitation of the supply 85 of motive fluid to the front end of the cylinder and the other means operating by discharge of motive fluid from the front end of the cylinder, said discharge means being covered by the valve during the forward 90 stroke.

6. In a fluid pressure actuated tool, the combination of a cylinder having a piston chamber, a piston reciprocable in the chamber, valve means for controlling the movements of the piston including a reciprocatory valve member, and means controlled by the movement of the valve member to effect the return of the piston whereby to connect the forward portion of the piston chamber 100 with the atmosphere as the piston approaches the rear end of its travel.

7. In a fluid pressure actuated tool, the combination of a cylinder having a piston chamber, a piston reciprocable in the chamber, a reciprocatory valve member, means controlled by the forward movement of the piston to shift the valve member, means for supplying a restricted amount of pressure fluid to the front end of the piston chamber 105 to return the piston, means independent of the two last mentioned means for holding the valve member in its rearmost position, and means controlled by the valve member and operable in the rearward movement of 110 the piston to decrease the returning speed of the latter and to facilitate the forward movement of the valve member.

8. In a fluid pressure actuated tool, the combination of a cylinder providing a piston chamber, valve means including a reciprocatory valve member, means controlled by the movements of the piston for shifting the valve member in opposite directions, and means controlled by the valve member and operable as the piston moves toward its initial position to decrease the returning speed of the piston and to facilitate the shifting of the valve member.

9. A fluid pressure actuated tool having 130

a reciprocating piston, a valve controlling the movements of the piston, a valve-control passage uncovered by the piston toward the end of the forward stroke for shifting the valve, means for again shifting the valve toward the end of the rearward stroke, means for trapping pressure fluid received from the valve control passage during the forward movement of the piston 5 to hold the valve in its rearward position, and discharge means associated with the valve-control passage and uncovered by the valve during its rearward stroke whereby uncovering the valve-control passage by the 10 piston on its return stroke will operate during the remainder of the stroke to reduce the pressure in the forward piston chamber.

10. A fluid pressure actuated tool having a reciprocating piston, a passage opening at 20 one end into the piston chamber at its mid-portion, an exhaust duct, a port communicating with the other end of said passage, and a valve adapted in one position to establish communication between said port and said 25 duct and in another position to close said port and cut off communication between the passage and said duct.

11. A pressure fluid actuated tool having a cylinder, a piston reciprocable in the cylinder, a reciprocating valve, inlet and exhaust 30 passages controlled by said valve, the exhaust passage being located near one end of the valve, a valve-control passage opening into the mid-portion of the cylinder and 35 adapted to be uncovered by the forward end of the piston as it travels rearwardly and a port communicating at all times with said control passage and adapted to communicate under the control of the valve with the 40 exhaust passage.

12. A pressure fluid actuated tool having a reciprocating piston, a reciprocating valve, inlet and exhaust passages controlled by opposite ends of said valve, a valve-control 45 passage opening into the mid-portion of the cylinder and adapted to be uncovered by the forward end of the piston as it travels rearwardly, means controlled by the valve operating when the valve is in its rearmost 50 position to supply pressure fluid to the forward piston chamber to move the piston rearwardly, and a port communicating at all times with said control passage and with said exhaust passage when the valve member 55 is in its rearmost position.

13. A pressure fluid actuated tool having a reciprocating piston, a control valve having large and small pressure chambers, means for supplying pressure fluid to the small 60 pressure chamber to shift the valve in one direction, and means for shifting the valve in the opposite direction including a valve control passage opening into the mid-portion

of the piston chamber and communicating at its rear end with the large pressure chamber in the forward position of the valve, and a port for supplying pressure fluid from said control passage to the forward end of the valve whereby to assist in shifting it rearwardly. 65

14. A pressure fluid actuated tool having a reciprocating piston, a control valve having large and small pressure chambers, means for supplying pressure fluid to the small pressure chamber to shift the valve in 70 one direction, and means for shifting the valve in the opposite direction including a valve-control passage opening into the mid-portion of the piston chamber and communicating at its rear end with the large pressure chamber in the forward position of the valve, and a port for supplying pressure fluid from 75 said control passage to the forward end of the valve whereby to assist in shifting it rearwardly, said port communicating with the atmosphere in the rearward position of the valve member whereby, when the piston in its rearward travel uncovers the forward end of said control passage the forward piston chamber is also connected with the atmosphere. 80

15. A pressure fluid actuated tool having a reciprocating piston, a control valve, means operating during the rearward stroke of the piston to hold the control valve in its rearward position, means operating as the piston approaches the rear end of its stroke to move the valve to its forward position, passages arranged to be connected in the rearward travel of the piston and operating to hold the valve member rearwardly, and a port connecting one of said passages with the atmosphere in the rearward position of the valve member whereby to reduce the pressure in the forward piston chamber. 95

16. A pressure fluid actuated tool having a reciprocating piston, a control valve, inlet and exhaust passages controlled by said valve, the exhaust passage being adapted to be closed by the forward end of the valve in the initial portion of its forward movement, a valve-control passage opening into the mid-portion of the cylinder and adapted to be uncovered by the rear end of the piston as it approaches the forward end of its stroke, and a port leading from said valve-control passage to the extreme forward end of the valve chamber so as to admit pressure fluid from the control passage to the extreme forward end of the valve after the latter closes said exhaust passage, whereby to retard the final portion of the forward movement of the valve. 100

In testimony whereof, I have hereunto set my hand.

ERNEST H. SHAFF.
